UNITED STATES PATENT OFFICE.

LEVI S. BACON, OF WASHINGTON, DISTRICT OF COLUMBIA, ASSIGNOR TO
DAVID S. WEGG, OF CHICAGO, ILLINOIS.

BONDING-PIN.

SPECIFICATION forming part of Letters Patent No. 671,009, dated April 2, 1901.

Application filed November 19, 1900. Serial No. 36,949. (No model.)

To all whom it may concern:

Be it known that I, LEVI S. BACON, a citizen of the United States, residing at Washington, in the District of Columbia, have invented certain new and useful Improvements in Bonding-Pins; and I do hereby declare the following to be a full, clear, and exact description of the invention, such as will enable others skilled in the art to which it appertains to make and use the same.

This invention relates to an improvement in bonding-pins for electric railways, and is embodied in the construction and arrangement of parts presently to be described, and defined in the claim.

Heretofore it has been suggested to construct a bonding-pin of frusto-conical formation and to form in the side thereof a channel for the wire, the channel being of varying depths. It has also been suggested to form a pin with parallel sides or cylindrical in cross-section and having a channel therein of uniform depth and forming the extreme end of the pin somewhat tapered, the channel at that point being of varying depths. Both constructions have been found objectionable in some respects and so largely because an unequal pressure is brought to bear on the wire owing to the varying depths of the channel, which in many cases would tend to break or indent the wire when the pin is driven into the rail-opening, thus materially affecting the durability and permanency of the connection. I have found that this objection can be largely overcome by utilizing the principle of the former constructions as to the uniform taper throughout and applying the channel form of the latter—namely, a cylinder with a channel of uniform depth throughout; and with that intention my invention may be stated as consisting in a bonding-pin tapered

throughout and having a receiving-channel for the wire of uniform depth throughout.

In the drawings, Figure 1 represents a pin in side elevation, showing the base of the channel in dotted lines. Fig. 2 is a longitudinal section. Fig. 3 is an end view. Fig. 4 is a view of a modified form.

A designates the pin proper, which is tapered throughout and has formed in one side thereof the open wire-receiving channel B, which is of uniform depth throughout. The pin A may be conical in formation or have one side, as at a, Fig. 4, straight as distinguished from tapering. In both cases, however, there is a wedging portion or surface and the channel is made of uniform depth, so that the wire will be firmly held throughout and a uniform portion thereof permitted to project beyond the plane of the edge of the pin.

The above construction is regarded of importance, overcoming, as it does largely, the objection to the skiving or cutting of the wire in the act of inserting the pin in the rail-opening.

Other important advantages are also gained, among which may be stated that of simplicity of structure and ease of manufacture.

Having thus described the invention, what I claim as new, and desire to secure by Letters Patent, is—

A bonding-pin tapered throughout and having an open-sided longitudinal channel therein extending from end to end and of uniform depth throughout, substantially as described.

In testimony whereof I affix my signature in presence of two witnesses.

LEVI S. BACON.
